UNITED STATES PATENT OFFICE.

PIERRE CHEVENARD, OF IMPHY, FRANCE, ASSIGNOR TO SOCIETE ANONYME DE COMMENTRY, FOURCHAMBAULT & DECAZEVILLE, OF PARIS, FRANCE.

INDUSTRIAL APPARATUS FOR THERMOMETRIC ANALYSIS.

Application filed February 7, 1922. Serial No. 534,732.

To all whom it may concern:

Be it known that I, PIERRE CHEVENARD, a citizen of France, and a resident of Imphy, Nièvre, France, have invented new and useful Improvements in Industrial Apparatus for Thermometric Analysis, which is fully set forth in the following specification.

The present invention has for its object an improved industrial apparatus for thermometric analysis and which is simple and strong, and even when hurriedly installed and entrusted to an operator of but little experience, yields very definite results which can be turned to immediate account; moreover, the simplicity of its construction permits of its being produced at a moderate price. These combined qualities adapt the improved apparatus for precise experiments carried out in research laboratories, for instruction purposes and for industrial decisions. It is particularly useful in thermometric operations for determining the hardening properties of alloys and principally of steels.

The apparatus when in operation inscribes two curves simultaneously on a sheet of diagram paper mounted on a chronograph cylinder; the first expresses the variations of the temperature of the substances under examination, the indication of these variations being caused by changes in length of a needle made of special alloy and engaging with slight friction in a hole bored through the specimen; the second shows the thermometric expansion of the specimen. The special alloy used in the construction of the needle is, preferably, the alloy disclosed in my U. S. Patent No. 1,489,116, dated April 1st, 1924. This alloy is preferably formed of the following elements—Nickel or cobalt, 70% to 90%; chromium, 10% to 25%; tungsten, 0% to 5%; carbon, 0.2% to 0.6%; manganese, 1% to 3%.

If necessary the tungsten may be replaced by an equivalent quantity of molybdenum, and the alloy may have added thereto vanadium 0% to 1%, titanium 0% to 5%, uranium 0% to 0.5%, boron 0% to 0.5%, zirconium 0% to 0.5%, for the purpose of facilitating the metallurgical elaboration.

By the combined action of the chromium, manganese, carbon and, if desired, tungsten, etc., the point of transformation of the nickel or cobalt is reduced considerably below the ordinary temperature whereby the

alloy is entirely exempt from thermic anomalies.

The thermometric phenomena which accompany transformations of polymorphous substances determine the appearance of peculiarities in the temperature-time curve; but these peculiarities, which are very evident when the temperature rapidly varies, become, on the contrary, scarcely perceptible at low temperatures, when the rate of cooling is small.

The object of the curve of expansion is precisely to reveal all the manifestations of the transformation. In fact, changes in condition of most polymorphous substances are accompanied by a variation of volume, the extent of which is sensibly independent of the rapidity of the changes of temperature. In particular, in steels, in certain bronzes, in certain varieties of silica, etc., the amplitude of this change of volume is considerable: all the points of transformation are, therefore, shown very distinctly in the expansion curve, and it is sufficient to consider the corresponding point of the first curve in order to learn the temperature of the phenomenon.

The following description relative to the drawing, given by way of example, will explain the nature and advantages of the invention.

Figs. 1 and 2 show, in elevation and in plan respectively, with parts in section, an apparatus for thermometric analysis constructed according to the invention.

Fig. 3 is a view in detail of amplifying mechanism.

The specimen under examination *e*, carrying the pyrometric needle *a*, is placed in a tube *t* of moulded silica; the rounded point of the needle *a* and the hemispherical end of the specimen *e* impinge on the bottom of this tube *t*.

The mechanisms intended for amplifying the expansions of the needle and of the substance under examination are identical, dimensions being excepted; to facilitate the reading of the drawing the parts relating to the specimen *e* are indicated at *b'*, *c'*, *d'*, *f'*, *g'*, and those relating to the pyrometric needle *a* at *b²*, *c²*, *d²*, *f²*, *g²*.

The expansion, of the specimen *e* and of the pyrometric needle transferred to the outside of the furnace by rods *b'*, *b²* of silica prolonged by tongues *c'*, *c²* of tempered steel, is transmitted to the points *d'*,

d^2 of levers of the second class f' , f^2 , the fixed axes of which are determined by the points p' , p^2 . Beads or projections g' , g^2 of polished steel fixed to the end of movable levers f' , f^2 transmit the movement of the latter to blunt points h' , h^2 which form the ends of the short arms of bent levers k' , k^2 . The levers k' , k^2 , partially balanced by counterweights l' , l^2 , are movable about the horizontal axes m , and carry pens or styles n' , n^2 at the ends of their long arms; pens n' , n^2 record curves r' , r^2 on the cylinder g .

The two levers k' and k^2 are of exactly the same appropriate length and their axes m are in alignment with each other. Consequently, the corresponding points of the two curves occur on one and the same circular ordinate. The short arms of the levers f' and f^2 being unequal (see Fig. 3), the expansion of the specimen is less amplified than that of the needle; the meeting of the two pens is therefore impossible, even if the expansion of the substance under examination should be appreciably greater than that of the alloy forming the needle.

Owing to the power called into play during expansion, the apparatus possesses several essential qualities:

(1) Very great strength.

(2) Accuracy of indications and absence of delay in recording faultless phenomena, even if changes of temperature are very rapid.

(3) Complete immunity from shakings and disturbances due to friction, so that the curves traced by the apparatus are exact and endowed with very great clearness.

It is obvious that the arrangements which have just been described, by way of example, are by no means limiting and modifications may be applied to them without departing from the scope of the invention.

Having thus described the nature of the said invention and the best means I know of carrying the same into practical effect, I claim:—

1. A device of the class described comprising, in combination, a container, a specimen of the substance under examination placed in said container, a pair of rods operatively engaging said specimen, recording means engaging one of said rods for indicating variations in temperature of the specimen, and means engaging the other of said rods for indicating variations in expansion of said specimen.

2. Industrial apparatus for thermometric analysis comprising in combination, a tube, a specimen of the substance under examination placed in the tube, recording means operatively engaging said specimen for graphically indicating exteriorly of the tube the variations in temperature of the specimen, and means including a lever for

graphically indicating exteriorly of the tube the variations in the expansion of the specimen.

3. Industrial apparatus for thermometric analysis comprising in combination, a tube, a specimen of the substance under examination placed in the tube, means for transmitting to the outside of the tube and amplifying the variations of the temperature of the specimen, and means for transmitting to the outside of the tube and amplifying the variations in the expansion of the specimen.

4. Apparatus for thermometric expansion comprising a tube of silica, a specimen of the substance under examination placed in the tube, means for transmitting to the outside of the tube and amplifying the variations of the temperature of the specimen, and means for transmitting to the outside of the tube and amplifying the variations in the expansion of the specimen.

5. Apparatus for thermometric analysis comprising a tube, a specimen of the substance under examination placed in the bottom of the tube, an axial hole bored through the specimen, a needle located in the hole and impinging upon the bottom of the tube, means for transmitting to the outside of the tube the variations of the temperature of the specimen according to the variations of length of the needle resulting from the expansion of the needle, and means for transmitting to the outside of the tube the variations of the length of the specimen resulting from the expansion of the latter.

6. Apparatus for thermometric analysis comprising a tube, a specimen of the substance under examination placed in the bottom of the tube, an axial hole bored through the specimen, a needle located in the hole and impinging upon the bottom of the tube, means for transmitting to the outside of the tube and amplifying the variations of the temperature of the specimen according to the variations of the length of the needle resulting from its expansion, and means for transmitting to the outside of the tube and amplifying variations of the length of the specimen resulting from its expansion.

7. Apparatus for thermometric analysis comprising a tube, a specimen of the substance under examination placed in the bottom of the tube, an axial hole bored through the specimen, a needle located in the hole and impinging on the bottom of the tube and constituted by a special alloy comprising nickel, chromium, tungsten, carbon and manganese, means for transmitting to the outside of the tube variations of the temperature of the specimen according to the variations on the length of the needle resulting from its expansion, and means for transmitting to the outside of the tube vari-

ations of the length of the specimen resulting from its expansion.

8. Apparatus for thermometric analysis comprising a tube, a specimen of the substance under examination placed in the bottom of the tube, an axial hole bored through the specimen, a needle located in the hole and impinging on the bottom of the tube, and constituted by a nickel alloy disclosed in my U. S. Patent No. 1,489,116, dated April 1st, 1924, means for transmitting to the outside of the tube and amplifying the variations of the temperature of the specimen according to the variations of the length of the needle resulting from its expansion, and means for transmitting to the outside of the tube and amplifying variations of the length of the specimen resulting from its expansion.

9. Apparatus for thermometric analysis comprising a tube, a specimen of the substance under examination placed in the bottom of the tube, an axial hole bored through the specimen, a needle located in the hole and impinging on the bottom of the tube and constituted by a nickel alloy, means for transmitting to the outside of the tube and amplifying the variations of the temperature of the specimen according to the variations of the length of the needle resulting from its expansion, and means for transmitting to the outside of the tube and amplifying the variations of the length of the specimen resulting from its expansion, the amplification of these variations of length being different from the amplification of variations of the length of the needle, a recording cylinder, means for recording on this cylinder the variations transmitted to the outside of the tube and resulting from the needle and from the specimen.

10. Apparatus for thermometric analysis

comprising a tube, a specimen of the substance under examination placed in the bottom of the tube, an axial hole bored through the specimen, a needle located in the hole and impinging on the bottom of the tube and constituted by an alloy exempt from thermic anomalies, means for transmitting to the outside of the tube and amplifying the variations of the temperature of the specimen according to the variations of the length of the needle resulting from its expansion, means for transmitting to the outside of the tube and amplifying the variations of the length of the specimen resulting from its expansion, the amplification of these variations of length being different from the amplification of variations of the length of the needle, a recording cylinder, means for recording on this cylinder the variations transmitted to the outside of the tube and resulting from the needle and from the specimen.

11. Apparatus for thermometric analysis comprising a tube in which is positioned a specimen of the substance to be analyzed, a needle formed of an alloy exempt from thermic anomalies extending through the specimen, means operatively engaging said needle for amplifying variations in temperature of said specimen, means for amplifying variations in the expansion of said specimen, a recording cylinder, and means engaging said cylinder and cooperating with said temperature and expansion means for graphically recording said variations on the cylinder.

In testimony whereof I have signed this specification.

PIERRE CHEVENARD.
